} Inventors

Daniel L. Gold, of Springfield, Ill. and

John B. Adams,

Letters Patent No. 2,151. Dated Aug. 1, 1865.

Design for a Trade-mark.

The schedule referred to in these Letters Patent and making part of the same.

To all whom it may concern:

Be it known that we, Daniel L. Gold and John B. Adams, of the City of Springfield, County of Sangamon and State of Illinois, have originated and designed a new design for a trade-mark of which the following is a full, clear and exact copy, reference being had to the accompanying drawing, which is part of this specification. Our trade-mark label consists of the words -

"Old Pollock" Whiskey

D. L. Gold & Co.

successors to Dan Deem

Druggists and Chemists

West-Side, Capitol Square, Springfield, Ill.

arranged in the ornamental style and shape shown in the drawings.

What we claim as our invention and desire to secure is a new and useful and ornamental design for a stove for heating apartments or warming railway carriages; and I do hereby declare the same to be fully described in the following specification and represented in the accompanying drawings of which;

Figure 1 is a top view,

Figure 2, a front elevation,

Figure 3, a side elevation, and

Figure 4, a longitudinal section of the stove,

Figure 5, is a transverse section taken through the dome.

My improved stove, like others in use, has its fire-place or fire-pot A, its ash-chamber B, a grate C, and a conical dome D. The latter surmounting the fire-pot and being provided with a throat E.

for the passage of fuel into the fire-pot. The mouth of such throat is provided with a door F. The mouth of the ash-chamber, which is in the base-part G, of the stove, is also provided with a door or cover H, there being a sliding air register or valve in each of the said doors.

The fire-pot I, is an inverted frustum having on its exterior a series of lance heads a, a, a, in relief, their being arranged at equal distances apart.

At its upper edge the fire-pot is provided with an annular lip or flaunch b, which is capped by a similar lip or flaunch c, projecting from the bottom part of the dome D.

An annular fender or ring K, surrounds the flaunch c, and is supported by a series of arms d, d, d, d, which project from the fender and upon the top of the said flaunch.

The said dome D, is a conic frustum used open at top into a smoke-space or chamber L, which is surrounded by a circular cap or platform M, which projects beyond the dome and has a diameter about equal to that of the fender. This platform has a pot-hole F, arranged over the chamber L, and for the reception of a boiling vessel. A smoke escape flue or conduit, N, leads out of the chamber L, and up through the platform M, as shown in the drawings.

The fire dome is made with a series of horizontal arcs by Letters Patent, is the design for a trade-mark herein set forth and shown.

Witnesses.

E. F. Leonard,

Hall Wilson.

Daniel L. Gold.

John B. Adams.
